UNITED STATES PATENT OFFICE

MATTHEW GRANT, OF LOS ANGELES, CALIFORNIA

DESIGN FOR A FRUIT AND VEGETABLE PRESS

Application filed March 4, 1932. Serial No. 43,074. Term of patent 3½ years.

To all whom it may concern:

Be it known that I, MATTHEW GRANT, a citizen of the United States, residing at Los Angeles, in the county of Los Angeles and State of California, have invented a new, original, and ornamental Design for Fruit and Vegetable Presses, of which the following is a specification, reference being had to the accompanying drawings, forming part thereof.

Fig. 1 is a side elevational view of a fruit and vegetable press, showing my new design, and Fig. 2 is a perspective view thereof, on a larger scale.

I claim:

The ornamental design for a fruit and vegetable press as shown and described.

MATTHEW GRANT.
